UNITED STATES PATENT OFFICE.

AUGUST H. JAHN, OF HOMESTEAD, PENNSYLVANIA.

ELECTRIC-COMMUTATOR CLEANER.

SPECIFICATION forming part of Letters Patent No. 654,734, dated July 31, 1900.

Application filed November 23, 1899. Serial No. 738,085. (No model.)

To all whom it may concern:

Be it known that I, AUGUST H. JAHN, a resident of Homestead, in the county of Allegheny and State of Pennsylvania, have invented a new and useful Improvement in Electric-Commutator Cleaners; and I do hereby declare the following to be a full, clear, and exact description thereof.

My invention relates to means employed for cleaning or grinding the commutator-cylinders of dynamo-electric generators and motors; and it has for its object to provide a device of the character indicated which shall be simple and inexpensive in construction and effective and durable in operation and one which is normally moved and held out of operative position automatically and may be thrown into operative position by closing a suitable switch located at any convenient point irrespective of the distance of such point from the mechanism.

It is well known to users of electric motors and generators that in normal use dirt accumulates on the commutator-cylinders and that unless such dirt is removed at intervals the conductivity is impaired to such an extent as to involve objectionable sparking at the brushes. This is especially true of motors employed for propelling railway-vehicles, and it has been the usual practice to clean the commutators of such motors by hand at comparatively-frequent intervals. This process involves removing the motors temporarily from service and opening up the frames sufficiently to secure access to the commutator-cylinders. It also necessitates the expenditure of considerable labor and is therefore a matter of considerable expense. The unequal wearing of commutator-cylinders in certain machines also often necessitates the grinding of such cylinders by means of sand or emery paper in order to secure a uniform contact-surface, as well as to remove the accumulated dirt.

The mechanism that I have devised for use in lieu of hand-cleaning means is shown in the accompanying drawings, in which—

Figure 1 is an end elevation of a portion of the commutator and of my cleaning device. Fig. 2 is a side elevation of the apparatus shown in Fig. 1, and Fig. 3 is a detail view.

The portion of the commutator-cylinder 1

on which the brushes bear is shown at 2, the portions 3 being projections to which the commutator-leads are connected.

55

The mechanism for cleaning the commutator-cylinder is mounted in a suitable frame 4, provided with openings 5, through which screws or bolts may be inserted to fasten the frame to the frame of a motor or to any suitable support in order that the working parts may be operatively located. The frame 4 contains a solenoid 6, the core 7 of which is movable vertically and is connected to the inner ends of two levers 8 by means of a pin 9, the ends of the levers being provided with slots 10 to receive the pin 9. Each of these levers is pivoted in a downwardly-projecting arm of the frame 4 and extends outwardly, its outer end being connected to a holder 12 by means of a rod 13 and links 14. The holder 12 is provided with a recess, the outer sides of which are beveled, as indicated at 15, and in this recess fits a block 16 of suitable abrading material or a wooden or other block, the face of which has fastened to it by means of glue or other suitable cement one or more layers or sheets of abrading material. The face of this block 16 is curved to conform to the surface of the commutator-cylinder, and its sides and top are of such contour as to fit the recess in the holder 12. The inclination of the sides 15 of the recess in the holder and the corresponding inclination of the upper portions of the sides of the block 16 are such as to insure a secure engagement between the said parts, while the form and relative size of the parts are such as to permit of a ready insertion and removal of the block. The arms 11, in which the levers 8 are pivoted, are provided with stops 17, with which the holder 12 engages when raised. In some cases the solenoid-core 7 may be heavy enough to raise the holder 12 and block 16 from the commutator-cylinder when the solenoid is de-energized; but ordinarily it will be found advisable to employ springs for supplementing the force exerted by gravity upon the solenoid-core. I have shown two such coiled springs 18, the lower ends of which are attached to lugs on the upper side of the holder and the upper ends of which are attached to suitable projections on the solenoid-core. I have shown a circuit 19 20 supplied with energy

from a battery 21 for energizing the solenoid, the circuit being opened and closed by means of a suitable switch indicated diagrammatically at 22; but in the case of a railway or other motor, and, in fact, generally, the current may be taken from the dynamo-circuit for energizing the solenoid.

It will be readily understood without further description that when it is desired to 10 clean the commutator it will be rotated, preferably, as for normal operation, and the circuit of the solenoid will be closed, thus raising the core, and thereby pressing the block into contact with the commutator-cylinder 15 through the action of the levers and links.

I desire to be understood that my invention is not limited to the exact details of construction shown, since modifications as regards the number, form, and location of parts may be 20 readily made without materially changing the mode of operation or result.

What I claim as my invention, and desire to secure by Letters Patent, is—

1. In a cleaning or grinding device for commutator-cylinders, the combination with a 25 supporting-frame, of a holder containing a cleaning-block and movable toward and away from a commutator-cylinder, a pair of levers pivoted in said frame, links connecting said 30 holder with the outer ends of the levers, a solenoid and a core therefor having a slot-and-pin connection with the inner ends of said levers.

2. In a cleaning or grinding device for commutator-cylinders, the combination with a 35 frame and a movable holder for cleaning material, of a solenoid, a core and lever-and-link connections between the core and the holder whereby the latter is moved toward the commutator-cylinder when the solenoid is energized, substantially as set forth.

3. In a cleaning or grinding device for commutator-cylinders, the combination with a frame and movable holder for cleaning material, of a solenoid, a core and lever-and-link 45 connections between the core and the holder, whereby the latter is moved toward the commutator-cylinder when the solenoid is energized, and springs acting to retract the holder when the solenoid is deenergized.

4. In a cleaning or grinding device for commutator-cylinders, the combination with a frame and a movable holder for abrading material, of a solenoid, a core and lever-and-link 50 connections between the core and the holder, whereby the latter is moved toward the commutator-cylinder when the solenoid is energized, and one or more coiled springs 55 connecting the solenoid-core with the holder and placed under tension when the solenoid is energized.

5. In a cleaning or grinding device for commutator-cylinders, a holder for a cleaner-block, provided with a recess of dovetail shape and a removable cleaner-block fitting in said 65 recess, in combination with a supporting-frame, a solenoid, a core and operating-levers intermediate the core and the holder, substantially as set forth.

6. In a cleaning device for commutator-cylinders, a holder and a cleaner-block located in a recess therein and laterally removable therefrom, in combination with a solenoid, a core, and operating-levers connecting the core to the holder, substantially as set forth.

In testimony whereof I, the said AUGUST H. JAHN, have hereunto set my hand.

AUGUST H. JAHN.
